UNITED STATES PATENT OFFICE

HACHIG A AYVAD, OF WEST NEW YORK, NEW JERSEY

HAMMER

Application filed October 26, 1925, Serial No. 64,736. Renewed January 6, 1928.

The object of this invention is to provide a claw hammer with manifold features which are useful particularly for those who are engaged in the opening and closing of boxes for the packing and shipping of goods, and for others who may need a tool with a wider range of usefulness than the usual type of claw-hammer. A further object is to impart balance to the hammer by providing beyond the line of the face sufficient weight so that its momentum will substantially balance the momentum of the handle, and when striking a blow the momentum of substantially the entire hammer will be absorbed at the point where the blow is delivered and none will be transmitted to the hand so that the hand will be relieved of all shock. Other objects are to provide a hammer which is suitable for extracting nails of a considerable range of sizes and from a position, as in a corner, which is inaccessible to a claw of the usual type. A further object is to provide means for bending a nail from which the head has broken off so that it can be engaged by the claw and extracted. A further object is to provide a hammer by which a nail may be completely extracted in one operation even when of such length that with a claw hammer of the usual type a block would need to be set under the hammer after partial extraction. A further object is to provide a hammer with a chisel edge transverse to the axis of the eye through the poll and suitably disposed for use in trimming the edge of a board or for use as a scraper for removing old markings.

In the accompanying sheet of drawings which forms a part of this description,

Fig. 1 is a perspective of a hammer head embodying this invention, a portion of the helve being indicated in dotted lines;

Fig. 2 is an elevation of the hammer head; and

Fig. 3 is a longitudinal section through the hammer head.

The hammer head comprises the customary poll 10 which is elongated and the eye through which is tapered slightly to within three-quarters of an inch of the outer end from which point it is flared slightly. In the sides of this flared portion are grooves 11 which

serve to guide the wedges which are driven into the end of the helve to secure the helve in the head.

Projecting from the side of the poll is the hammer face 12 which is set below the end of the poll so as to leave at top of the poll a fulcrum shoulder 13 about which the hammer can be rocked through a considerable angle when set against a board for the purpose of pulling a nail. On the opposite side of the poll from the hammer face is a curved nail-engaging portion 14 which projects from the poll at its outer end wholly beyond the axis X—X of the face, and it is not curved as much as the usual claw of a claw-hammer so that the major part of the weight which it adds to the hammer head is beyond the axis of the face and its momentum serves to balance the momentum of the handle to such an extent that none of the shock of arresting the motion as a nail is struck will be felt by the hand. This weight beyond the axis of the face is not sufficient to balance the weight of the handle and bring the center of gravity into the axis, for what is required is to balance the momentum, which for any part is measured by the product of the weight of the part multiplied by the square of its velocity. A hammer in striking a blow traverses a curved path so that its outer portion has a considerable velocity compared with the handle and brings the point of momentum balance, known as the center of percussion, sufficiently close to the axis of the face to eliminate shock to the hand.

A chisel edge 15 is provided at the outer end of the curved nail-engaging portion and this edge is transverse to the axis Y—Y of the eye through the poll. Since the curvature of the nail-engaging portion is less than is customary, and preferably limited as shown to approximately forty-five degrees, this chisel edge is in a suitable direction for chipping away the edge of a board such as the tongue or groove at the side of a box when the cover, after having been nailed on, is found to project beyond the edge of the box.

Provision is made for nail extraction without breaking the chisel edge by the nail-engaging notch of the usual claw. Instead

a slot 16 is provided in the curved portion. This slot has an enlarged portion 17 near the end remote from the poll which is sufficient for any ordinary nail head to pass therethrough. From this opening the sides 5 converge toward the poll and make an acute angle with the upper face after the manner of the usual claw so that the shank of a nail can be engaged under the head for extraction, but the sides do not come together at a point and the heads of small nails and brads cannot be engaged. Instead the sides run into an eye 18 at the end nearest the poll. This eye is large enough to receive the shank of a nail when the head 10 has been broken off and affords a means for engaging and bending over the shank so that it can be taken hold of and extracted. From the main enlarged portion the sides of 15 the slot converge to a point 19 away from the poll to provide a means for engaging and extracting small nails and brads. All of these instrumentalities for extracting nails are part of one unitary slot for convenience of manufacture and so that the forming dies may be of a rugged character.

In addition to the central curved nail-engaging portion there are nail-engaging side claws 20 in which the outer sides of the 20 claws are flush with and protected by the sides of the central nail-engaging portion beyond the points of the claws, so that when the hammer is laid down these claws will not scratch the surface on which it is laid. These 25 are provided for extracting nails from walls at points close to floors, or from floors close to walls and from similar confined places where the nails are inaccessible to the other means for extraction.

40 I claim,—

In a hammer, the combination with a helve-receiving poll, of a curved nail-head engaging portion terminating in a chisel edge notched at the sides to form nail-engaging side claws in which the outer sides of 45 the claws are protected by the sides of the curved nail-engaging portion and the chisel edge is beyond the notches for the side claws.

50 HACHIG A AYVAD.
